UNITED STATES PATENT OFFICE

126,410

DESIGN FOR A TEXTILE FABRIC

Allan Zimmerman, New York, N. Y.

Application January 15, 1941, Serial No. 98,059

Term of patent 3½ years

To all whom it may concern:

Be it known that I, Allan Zimmerman, a citizen of the United States, residing at 37 Riverside Drive, in the city of New York, county of New York, and State of New York, have invented a new, original, and ornamental Design for a Textile Fabric, of which the following is a specification, reference being had to the accompanying drawing, forming part thereof.

The figure is a plan view of a piece of the fabric showing my new design.

I claim:

The ornamental design for a textile fabric, substantially as shown.

ALLAN ZIMMERMAN.
